UNITED STATES PATENT OFFICE.

RICHARD F. MASON, OF BISHOPVILLE, SOUTH CAROLINA, ASSIGNOR OF ONE-HALF TO
CHARLES A. DIVINE, OF FRANKLIN, NORTH CAROLINA.

DRILLING-MACHINE.

1,010,657.

Specification of Letters Patent.

Patented Dec. 5, 1911.

Application filed March 22, 1911. Serial No. 616,138.

To all whom it may concern:

Be it known that I, RICHARD F. MASON, a citizen of the United States, residing at Bishopville, in the county of Lee and State of South Carolina, have invented certain new and useful Improvements in Drilling-Machines, of which the following is a specification.

This invention relates to machines for 10 drilling a series or group of holes according to a pattern.

It is the object of the present invention to provide a multiple-spindle drilling machine of the kind stated embodying certain novel 15 structural details to be hereinafter described and claimed.

The invention also has for its object to provide improved means for feeding the drills into the work, a cam-actuated lever being provided which engages the drill spindles to depress the same.

In order that the invention may be better understood, reference is had to the accompanying drawings forming a part of this 25 specification, in which—

Figure 1 is an elevation of the machine; Fig. 2 is a plan view, and Fig. 3 is a sectional detail on the line 3—3 of Fig. 1.

Referring specifically to the drawings, 5 30 denotes the frame of the machine, said frame being suitably arranged to support the several parts to be hereinafter described.

The work is clamped on a carriage 6 which is slideable on balls 7 which latter run 35 in grooves 8 in a sub-carriage 9 mounted on balls 10 running in grooves 11 formed in a suitable support carried by the frame of the machine. The grooves 8 and 11 run at right angles with respect to each other so that 40 the work may be shifted about in any direction in a horizontal plane. The pattern is carried on a block 12, and a tracer 13 secured to the carriage 6, and co-operating with the pattern, shifts the carriage in a 45 well known manner.

At 14 are indicated the drill spindles, they being arranged vertically, and supported for rotary and sliding movement in the direction of their length, by suitable bearings

carried by horizontal arms 15 of the supporting frame. Above the lower horizontal arm, the spindles are fitted with set collars 16 between which collars and the arm coiled springs 17 are interposed, said springs being provided for the purpose of elevating 50 the spindles at the end of their working stroke. The spindles are geared together by pinions 18, and on one of the spindles is mounted a drive pulley 19 suitably connected to the source of power. One of the 55 pinions 18 is in mesh with a pinion 20 carried by a sleeve 21 which is loose on a shaft 22 and is held in place thereon by a set collar 23. This sleeve also has a pinion 24 which is in mesh with a spur wheel 25 fast 60 on a shaft 26. The shafts 22 and 26 are vertical and supported by bearings carried by the arms 15. On the shaft 26 is also made fast a pinion 27 which is in mesh with a spur 65 wheel 28 carried by one of a pair of clutch 70 members mounted on the shaft 22, said member being a sleeve 29 loose on said shaft. The other one of the clutch members is a sleeve 30 which is splined on the shaft 22. The opposite ends of these two 75 clutch sleeves have teeth which are adapted to interlock, and when in this position the motion of the sleeve 29 is transmitted to the shaft 22. When the sleeves are disconnected, the sleeve 29 runs idle and no motion is 80 transmitted to the shaft 22. A lever 31 is provided for shifting the clutch member 30, said lever being pivoted to an upright 32 of the supporting frame, as indicated at 33, and operatively connected to the clutch 85 member in any suitable manner.

The upper end of the shaft 22 carries a cam wheel 34 arranged horizontally, the lower edge of the rim of said wheel being shaped to produce a cam. The cam surface 90 at the point 35 is not as low as the cam surface at the point 36 which gives a very gradual downward movement to the drill spindles with one revolution of the cam wheel. The cam wheel herein described is located 95 above the drill spindles, and between said wheel and the upper ends of the drill spindles is interposed a lever 37 which is pivoted

at 38 to the upright 32 to swing in a vertical plane. This lever carries a roller 39 which is in engagement with the cam. The shaft of the roller is journaled in suitable bearings 40 carried by the top of the lever 37. The lever 37 also carries adjusting screws 41 which are so located that they are in contact with the upper ends of the drill spindles 14. These screws permit close adjustment of the length of the drill spindles and they are secured in adjusted position by lock nuts 42. The top edge of the cam wheel 34 is engaged by a roller 43 supported by bearings 44 carried by horizontal arms 45.

15 To the free end of the lever 37 is also connected one end of a coiled spring 46, the other end of which is connected to a stem 47 adjustably supported on a bracket arm 48 by means of pins 49 passing through two of 20 a series of holes in said stem, the adjustment of the stem being for the purpose of regulating the tension of the spring. The function of the spring 46 is to yieldingly hold the roller 39 in contact with the cam 34.

25 From the periphery of the cam wheel 34 projects a lug 50 which is adapted to be engaged by a holding device for locking the cam wheel, said holding device comprising a lever 51 which is pivoted at 52 to the upright 32, and has, adjacent to its free end, a notch 53 adapted to be entered by the lug. The lever 51 is connected to the lever 31 by a bar 54 connected at its lower end by a wire 55 to a foot pedal 56. To the other 30 end of the bar 54 is fastened one end of a coiled spring 57, the other end of which is made fast to a stem 58 which is adjustably mounted in the same manner as the stem 47. The spring 57 normally holds the lever 51 35 in a position to lock the cam wheel, and the lever 31 in a position to disengage the clutch member 30 from the clutch member 29. When the cam wheel is locked the lug 50 seats in the notch 53.

40 45 The operation of the machine is as follows: The work mounted on the carriage 6 is shifted about by means of the tracer 13. After the work has been properly positioned with respect to the drill spindles, the latter 50 are depressed to effect the drilling operation, this being accomplished in the following manner: The drill spindles 14 are rotated together through the gears 18. One of these gears transmits the rotary motion 55 of the spindles to the gear 20, and through the gears 24 and 25 motion is transmitted to the shaft 26. Upon depressing the foot pedal 56, the clutch member 30 is engaged with the clutch member 29 so that the motion 60 of the shaft 26 is now transmitted, through the gears 27 and 28, and the clutch mechanism, to the shaft 22. Simultaneous with the engagement of the clutch member 30 with the clutch member 29, the lever 51 is swung downwardly and disengaged from the lug 50, thus releasing the cam wheel 34, so that it may rotate with the shaft 22. The rotation of the cam wheel, by reason of its engagement with the roller 39, depresses the lever 37, and this motion of the lever is transmitted through the adjusting screws 41 to the drill spindles 14, thereby feeding the latter downwardly into the work. At the end of the downward feed of the drill spindles, the springs 17 elevate the same to 75 their normal position, said springs being compressed as the spindles are fed downwardly. The pedal will also be released, whereupon the spring 57 swings the lever 31 in a direction to disengage the clutch members 29 and 30 and at the same time to place the lever 51 in a position to lock the cam wheel, the free end of said lever extending into the path of the lug 50 so that the latter may slip into the notch 53 when it reaches 80 the same. That portion of the lever 51 which is adjacent to the notch 53 is shaped so that the lever snaps over the lug 50 when the latter reaches the notch. The width of the pinion 20 is such that the pinion 18 will 85 not become disengaged therefrom during the longitudinal movement of the drill spindles.

85 I claim:

1. In a drilling machine, a drill spindle, a cam wheel rotatable behind the spindle, a lever located between the cam and the spindle to feed the same, driving means for the cam wheel, a clutch for the driving means, a lock for the cam wheel, and means for simultaneously actuating the clutch and the lock.
2. In a drilling machine, a drill spindle, a cam wheel rotatable behind the spindle, a lever located between the cam and the spindle to feed the same, driving means for the cam wheel, means for throwing said driving means into and out of gear, and a lock for the cam wheel.
3. In a drilling machine, a drill spindle, a pinion on the spindle, a cam wheel, a shaft on which the cam wheel is mounted, a sleeve loose on the cam wheel shaft, a pair of pinions on the sleeve, one of said pinions meshing with the pinion of the spindle, a second shaft, a spur wheel on said second shaft in mesh with the other one of the pinions of the sleeve, clutch members on the cam wheel shaft, one of said members being geared to the second shaft, and the other member having a driving connection with the cam wheel shaft, and a lever located between the cam wheel and the spindle to feed the same.
4. In a drilling machine, a drill spindle, a cam wheel rotatable behind the spindle, a lever located between the cam wheel and the

spindle to feed the latter, driving means for the cam wheel, a clutch for the driving means, a lever for operating the clutch, a lug extending from the cam wheel, a lever having a notch in which the lug is adapted to seat whereby the cam wheel is locked, and a connection between said lever and the clutch lever whereby the notched lever is

operated to release the cam when the clutch is thrown.

In testimony whereof I affix my signature in presence of two witnesses.
